CONSTANT CURRENT SYSTEM

Hugh E. Young, Chicago, Ill.

Application July 29, 1935, Serial No. 33,706

8 Claims. (Cl. 171—119)

The present invention relates primarily to constant current systems, wherein a substantially constant potential is taken from an alternating current supply circuit and is transformed or translated into a substantially constant current in the load circuit. One effective method heretofore employed for transforming from constant potential to constant current has been by the interposition of a "monocyclic square" between the supply circuit and the load circuit. This monocyclic square is a bridge network comprising inductive and capacitative reactances connected alternately in series. The supply circuit is connected across the input diagonal of this monocyclic square, and the load circuit is connected across the output diagonal of the square. These constant current systems have particular application to street lighting systems in which a variable number of illuminating units are connected in series and form the load circuit. In such a system, it is necessary or desirable to maintain substantially constant current in the load circuit, notwithstanding the fact that the potential of the load circuit will vary with the number of illuminating units effective therein.

One of the principal objects of the invention is to provide an improved monocyclic constant current system characterized by an improved method of and apparatus for regulating the system. In this regard, one of the features is the provision of an improved regulating arrangement which is effective to control the potential of the supply circuit. One operating difficulty in these monocyclic constant current systems is that the load current in the load circuit varies with changes in the potential of the supply circuit, and this variation is, in many cases, undesirably large. In attempting to avoid this operating difficulty, it has heretofore been proposed to perform a regulating function in the nature of a short-circuiting control on the secondary or output side of the monocyclic square, but this method of regulation has not been satisfactory. My improved method of regulation goes directly to the source of the difficulty, i. e., the variations in the potential of the supply circuit, and exercises an improved potential regulating control on the supply circuit or on the primary side of the monocyclic square.

Another object, characterizing certain embodiments of my invention, is to provide an improved arrangement wherein the operation of the regulating apparatus is made responsive to the current flow in the load circuit.

Another object of the invention is to provide an improved monocyclic constant current system in which the load circuit, the load units and the associated apparatus will be protected from destructive voltages in the event of an accidental interruption of the load circuit.

Other objects and advantages of the invention will appear from the following detail description of certain preferred embodiments thereof. In the accompanying drawings Figures 1, 2, 3, 4 and 5 are circuit diagrams illustrating different embodiments of the invention.

Referring first to the embodiment illustrated in Figure 1, the alternating current supply line is represented by the two conductors 11, 12, and one or more constant current load circuits are indicated at 14, 14'. In the illustrated arrangement the load circuit 14 is an alternating current circuit and the load circuit 14' is a direct current circuit, each consisting of a conductor connected in series with the several current receiving devices 15. These constant current systems have particular utility for street lighting purposes, and accordingly the receiving units 15 may be regarded as lamps in a street lighting circuit, although it will be understood that the constant current load circuit might be employed to supply electric furnaces or other devices where constant current is a desideratum. It will be understood that where the load units 15 are lamps, each lamp will be provided with a conventional automatic cut-out or short circuiter (not shown) to prevent interruption to the line flow should the lamp burn out or be turned out; and such automatic cut-outs or short-circuters may also be provided where the load units are other types of devices. It will be seen that with the lamps connected in series, as shown, the resistance, and consequently the load of the line will vary with any increase or decrease of the number of lamps in use.

The transforming device for transforming the substantially constant potential of the supply circuit to the substantially constant current for each load circuit is represented by the monocyclic square, designated 16 in its entirety. The latter comprises two inductive reactances 17, 17' and two condensive reactances 18, 18' connected alternately in series in a bridge network. The alternating current supply line 11, 12 is connected to the primary side, or input diagonal of the monocyclic square, this input diagonal being represented by the two diagonally opposite points 19, 19'. The constant current load circuit has connection through conductors 22, 22' with the secondary side or output diagonal of the square, this output diagonal being represented by the diagonally opposite points 21, 21'. Preferably, the two inductive and the condensive reactances 17, 17' and 18, 18' are each of equal reactance. For proper operation of the system, it is desirable that there be an exact balance of the four reactances. Inasmuch as the capacity of the condensers produced in commercial manufacture may vary from the designed value to a certain ex-

tent, I find it preferable to provide the inductive reactances 17, 17' with several taps, as shown, to provide compensation for differences in the condensers. While I prefer to employ the monocyclic square type of transforming device in my improved constant current system by reason of better full-load efficiency, power factor, apparatus economy, etc., it will be understood that other transforming devices for transforming from constant potential to constant current may be employed between the supply circuit and the load circuit, such as a T-connection or resonating circuits utilizing inductive and condensive reactances.

15 A transformer 23 is preferably interposed between the monocyclic square 16 and the load, the primary of this transformer being connected with the conductors 22, 22', and the secondary of the transformer being connected with the series 20 load circuit 14. The use of said transformer enables the system to utilize standard condensers 18, 18' in the monocyclic square, while still adapting the resulting current to the proper value for street lighting circuits. In this regard, when the 25 proper balance of the four reactances 17, 17' and 18, 18' is made, the resulting constant current may not be of such value as to give the exact rated lamp current by the use of the normal or standard ratio of the transformer 23. Accordingly, either one or both windings of this transformer are therefore wound with several taps for additional compensation. The interposition of the transformer 23 between the monocyclic square and the load also serves to limit the rise 35 of voltage across the load circuit in the event of accidental interruption of the load circuit. A further safety device consists of a cut-out 27 connected across the secondary winding of the transformer 23, which cutout functions as a safety device in the event that frequency changes or the destruction or impairment of the regulating apparatus should cause an abnormal rise in the load voltage. The cut-out 27 may be of the film type in which an insulating film under normal 40 operating conditions renders the device non-conducting but which is broken down or punctured on application of an over voltage causing the device to act as a short circuit. The cut-out will short-circuit the secondary terminals of the 45 transformer 23 on the occurrence of an over voltage, and under this condition normal full current will flow through the short-circuited secondary coil of transformer 23 with no damage to the system. The load may consist of a single 50 alternating current load circuit 14, a single direct current load circuit 14', or a plurality of either or both of these circuits. In the case of the direct current load circuit 14', any suitable arrangement of rectifiers 28, 29 are included between the secondary of the transformer 23 and the 55 load units 15, the illustrated arrangement showing the rectifiers in such relation as to give a full-wave rectification. The cut-out 27 functions as a safety device in this direct current load 60 circuit in the same manner that it does in the alternating current load circuit.

The windings of relays 31, 31' are connected in series in the load circuits 14, 14' to be responsive to current flow therethrough. The contacts 32, 70 32' of these relays exercise a control over the phase of the voltage supply to the grids of the grid controlled arc rectifier tubes of the regulating apparatus, as I shall presently describe.

Referring now to this regulating apparatus, a 75 variable flux induction transformer 35 is connect-

ed to the supply line 11, 12. This transformer comprises three windings, namely, a primary winding 37 connected across the supply line, a secondary winding 38 connected in series in the supply line, and a control winding 39 which connects therewith in a regulating function for regulating the potential on the current supply line. These three windings are preferably mounted on the end and central legs of a transformer core structure 41, substantially as shown. Provision 5 is made for reversing the connection of the terminals of the secondary winding 38 in the conductor 12 of the supply line, as by throwing a reversible buck or boost switch 44 to one or the other of its two positions, whereby the secondary winding 38 can be connected either in a bucking or boosting relation in the supply line.

The control winding 39 of said transformer 35 is connected to the secondary winding 46 of a saturable core reactor 45. The primary winding 47 of the reactor 45 is connected through conductors 48 and 49 with the plate circuits of two grid-controlled arc rectifying tubes 51 and 52, which are adapted to supply a controlled direct current to said primary winding 47. The 10 anodes of these two tubes are supplied with alternating current potential through an anode or power transformer 53. The primary winding 54 of this transformer is connected across the supply line 11, 12 through conductors 56 and 57. 15 The terminals of the secondary winding 55 are connected through conductors 58 and 59 with the anodes or plates of the tubes 51 and 52. The conductor 48 extending from the primary 20 winding 47 of the saturable core reactor 45 has connection with a central tap on the secondary winding 55 of the anode transformer 53. The other conductor 49 leading from the primary winding 25 of the saturable core reactor has connection with a conductor 61 which establishes a cross connection between the filaments of the two tubes. The filaments of the tubes are heated through 30 any filament circuit, not shown. It will be seen from the foregoing that the two tubes perform full-wave rectification and supply a direct current to the primary winding 47 of the saturable core reactor 45. The value of this direct current 35 is dependent upon the conduction period of each tube in each alteration, and the length of this conduction period is determined by the grid potentials which control the time of firing or arcing 40 of the tubes.

One of the features of the invention is the use of a phase shifting or phase splitting method of grid control of these tubes for obtaining substantially instantaneous regulation of the potential supplied to the monocyclic square. This method of grid control employs a phase shifting network comprising a grid transformer 64, a resistor 67 and a reactance 68, 68'. The secondary winding 66 of the grid transformer has its terminals connected through conductors 71 and 72 with the grids of the two grid controlled arc rectifying tubes 51 and 52. A conductor 73 extends from a central tap of the secondary winding 66 and connects with the wire 61 which connects the two cathodes of the tubes. The primary winding 65 of the grid transformer has one terminal connected through conductor 75 with a central tap on the primary winding 54 of anode transformer 53. Extending from the two end terminals of said latter primary winding 54 are conductors 77 and 78 which form two branch paths both reuniting in conductor 79 which extends to the other terminal of the primary winding 65 75

of grid transformer 64. The resistor 67 is interposed in series in conductor 11. The reactance 68, 68' is interposed in series in the other conductor 78. The phase shifting control of the 5 grid voltage is effected by varying the reactance 68, 68'. This reactance comprises two sections, namely, the section 68 which is in the form of a variable inductance adapted to respond to the potential of the supply circuit 11, 12, and a 10 second section 68' of fixed reactance which is adapted to be inserted into or out of circuit by the relays 31, 31' in response to the current flow in the load circuits 14, 14'. The variable inductance 68 is preferably in the form of a 15 coil surrounding a movable plunger 81 of iron or other suitable magnetic material, which is movable to different positions within the coil. This plunger is pivotally connected with one end of a lever 82 mounted on an intermediate fulcrum 20 or pivot 83. Pivotally connected to the other end of said lever is a solenoid core or armature 84 which responds to the magnetic attraction of a coil 85. Said coil is connected in shunt across the supply line 11, 12 by the conductors 25 86 and 87. An adjustable tension spring 88 is connected between one end of the lever 82 and an adjusting member 89, such as a thumb screw, the latter enabling the spring to be adjusted to exert different degrees of tension on the lever 30 for obtaining the proper normal setting of the two cores 81 and 84, or for adjusting the apparatus to different ranges of voltage change. Other motion transmitting relations between the 35 two cores 81 and 84 may be adopted, although I regard the lever arrangement illustrated as preferable.

The other section 68' of the inductance in the phase shifting network is adapted to have a shunt placed across the same through conductors 91, 40 92 and 93 connecting in series with the contacts 32, 32' of the relays 31, 31' in the load circuits.

Referring now to the operation of the system, an increase of potential in the supply circuit 11, 12 acts through the potential coil 85 to increase 45 the magnetic attraction on the core 84, thereby depressing the other core 81 further into the variable inductance coil 68 and increasing the inductance in the branch circuit 78 of the phase shifting network. Increasing the inductance in 50 this branch circuit connecting with the primary winding of the grid transformer 64 shifts the grid voltage to an out of phase relationship to the anode voltage, or causes the grid voltage to become more out of phase relative to the anode 55 voltage than it was before this regulating operation. Shifting the phase relationship delays the firing or arcing of the tubes, viz., it shortens the conduction period of the tubes. The phase shifting arrangement disclosed enables the phase of 60 the grid voltage to be displaced from zero degrees phase angle, which has a conduction period of unity, to a phase angle of 180°—a complete phase splitting relation—which has zero conduction period. Referring again to the regulating operation, it will be assumed that the phase has been 65 shifted to a degree dependent on the rise of potential in the supply line, thereby shortening the conduction period and reducing the flow of direct current through the primary winding 47 of the saturable core reactor 45. This reduces the density of the flux which the direct current flow sets up in the core of the reactor. Accordingly, the reactance winding 46 of said reactor is enabled 70 to present a higher impedance to current flow 75 through the control winding 39 of the variable

flux induction transformer 35. The increased impedance to current flow through the control winding 39 permits a larger proportion of the primary flux to flow in the center leg of core 41, thus weakening the primary flux density in that 5 part of core 41 surrounded by coil 38. This, in turn, will cause the induced voltage in series coil 38 to be reduced, thus lowering the voltage in the supply feeder to the monocyclic network. Conversely, if the potential in the supply circuit 10 should decrease from its predetermined normal, the reduced magnetic attraction on the core 84 permits the other core 81 to move outwardly toward a position of lesser inductance within the 15 coil 68. The reduced inductance in the phase shifting network of the grid controlled arc rectifying tubes causes the grid voltage to become more nearly in phase with the anode voltage, thereby increasing the flow of current through 20 the tubes and through the direct current winding 47 of the saturable core reactor 45. The increased flux density thereby created in the core of said reactor reduces the impedance of the winding 46 and its connected control winding 39, 25 with the result of the passage of additional current in coil 39, which in turn increases the primary flux density in that part of core 41 surrounded by coil 38. This in turn will cause the 30 induced voltage in the series coil 38 to be increased, thus increasing the voltage in the supply feeder to the monocyclic network.

Referring now to the control exercised by the relays 31, 31' which are interposed in the load circuits 14, 14', the construction and arrangement of these relays are such that under normal current flow in the load circuit the relay contacts 32, 32' are closed. Hence, a shunt is normally maintained across the inductance 68' through the circuit 91, 92, 93, so that under these 40 conditions the phase shifting network is responsive solely to the changes of inductance which are caused in the variable inductance 68 by the change of potential across the supply line 11, 12. However, in the event that the current flow in 45 either load circuit should be interrupted, as by an accidental break in that circuit, the relay of that circuit is caused to open its respective contacts 32 or 32', thereby opening the short-circuiting shunt around the inductance 68'. This immediately increases the effective inductance in the 50 branch circuit 78 of the phase shifting network. As previously described, increasing the inductance in this circuit shifts the grid voltage relatively to the anode voltage and reduces the current flow through the tubes to the winding 47 of the saturable core reactor 45 which, in turn, causes the variable flux induction transformer 35 to reduce the potential supplied to the monocyclic squares. The inductance 68' is of sufficiently high value so that the phase shift caused by its introduction into the phase shifting circuit will reduce the potential supplied to the 55 monocyclic squares to the point where the dangers incident to a break in the load circuit are substantially eliminated.

Referring now to the embodiment illustrated in Figure 2, this system is substantially the same as the system of Figure 1, with the exception that the variable induction transformer 35 70 is omitted and the saturable core reactor 45 has its winding 46 placed in series with the supply circuit. As the potential in the supply circuit 11, 12 increases or decreases from a predetermined normal, the actuation of the cores 84 75

and 81 causes the inductance in the phase shifting network to be increased and decreased so as to control the value of the direct current flowing through the direct current winding 47 of the saturable core reactor 45. This reactor may exercise its potential regulating function on the supply circuit through the instrumentality of the variable flux induction transformer 35, in the same manner described of the embodiment illustrated in Figure 1. However, for the purpose of showing an alternative arrangement, I have illustrated the impedance winding 46 of the reactor as being connected directly in series in the supply circuit 11, 12. The same general mode of operation follows because increasing the flux density in the core of the reactor by an increased direct current flow through the winding 47 decreases the impedance of the winding 46 for increasing the potential in the supply circuit; and, conversely, reducing the flux density in the core of the reactor increases the impedance in the winding 46 for reducing the potential in the supply circuit. The first of these operations follows upon any tendency of the potential in the supply circuit to increase, and the latter of these operations occurs upon any tendency of the potential to decrease from a predetermined normal. In Figure 2 I have also illustrated an alternating current load circuit 14, and a direct current load circuit 14', either or both of which may be used.

Referring now to the modified embodiment illustrated in Figure 3, this system is substantially the same as the system disclosed in Figure 1, with the exception that the regulating function is made solely responsive to the current flow in the load circuit. The variable inductance apparatus which shifts the phase of the grid potential includes the same arrangement of inductance coil 68, core 81, lever 82, and core 84. In this instance, however, the core 84 responds to the magnetic attraction of a solenoid winding 85' which is connected in series in the load circuit. The load circuit may be an alternating current circuit 14 or a direct current circuit 14'. A rise of current in the load circuit above a predetermined value operates through the solenoid winding 85' and core 84 for increasing the inductance in the phase shifting circuit for reducing the potential of the supply circuit; and conversely a fall of current in the load circuit below a predetermined value operates to increase the potential of the supply circuit. Should more than one load circuit be used, a regulation responding to the current flow in one circuit affords adequate regulation for the other circuits as well. In this embodiment I have also shown the potential regulation as being effected through the medium of a saturable core reactor 45 having its reactance winding 46 connected in series in the supply circuit, although it will be understood that, if desired, the saturable core reactor may be arranged to control a variable flux induction transformer 35 for effecting the voltage regulation, as previously described of the embodiment shown in Figure 1.

Referring now to the embodiment illustrated in Figure 4, the potential coil 85 connected across the supply line operates through its core 84 to actuate a lever 101 in accordance with voltage changes in the supply line. This lever constitutes the movable element of a differential regulator, designated 100 in its entirety. Said lever is pivotally mounted at 102, and one end thereof carries a movable contact 103 adapted

to establish connection at different points with a resistance 104. The latter resistance is included in a circuit 105, 106 which connects with the terminals of the primary winding 47 on the saturable core reactor 45. The reactance winding 46 of said reactor may be included directly in the supply circuit 11, 12, or it may be connected to exercise control over the line potential through the instrumentality of a variable flux induction transformer 35, in the manner previously described in connection with Figure 1. The circuit 105, 106 is connected across a resistor 108 which is included in series in the anode circuit of the grid controlled arc rectifying tubes. The voltage drop across the resistor 108 is conducted through the circuit 105, 106 to the primary winding 47 of the reactor, the current flow from said voltage drop being subject, however, to the value of the variable resistance 104 as determined by the position of the lever 101. Tension springs 109, 109' connect with the lever 101 on opposite sides of the fulcrum 102, and have attachment to adjustable thumb screws 111, 111' or like adjusting means, whereby the tension of these springs can be adjusted. The tension of said springs may be adjusted for graduating the position of the movable contact 103 relatively to the pull of the solenoid core 84 and to the pull of another solenoid core 114 which is pivotally connected to the other end of the lever 101.

The latter core is movable within a coil 115, and responds to the current flow therethrough. This coil is connected in series in the anode circuit 116 of the rectifying tubes 51, 52, said anode circuit comprising the conductor 116a extending from the filaments to the coil 185 and resistor 108, the conductor 116b extending from the resistor 108 to the coil 115, and the conductor 116c extending from said latter coil to the central tap of the secondary winding 55 of anode transformer 53. Movable within the solenoid coil 185 is a core 184 which is pivotally connected to one end of the lever 182, fulcrumed at 183. The other end of said lever has the core 181 pivotally connected therewith which operates within the variable inductance coil 168 for varying the inductance of the phase shifting network associated with the rectifying tubes, in substantially the same manner as previously described in connection with Figure 1. Also, as previously described, a spring 188 connected between said lever and an adjustable point of attachment 189 controls the response of the lever 182 to the current flow through the coil 185. In the particular manner in which the lever 182, the two coils 168, 185 and their respective cores 181 and 184 function in this embodiment, said apparatus constitutes a constant current regulator for the anode circuit 116. For facility of reference, I have designated this constant current regulator 120 in its entirety.

The load circuits fed from the supply line 11, 12 through the monocyclic squares 16, 16' may be alternating current circuits or direct current circuits, as previously described.

Referring now to the operation of this embodiment, it will be seen that the lever 101 together with the two coils 85 and 115 and their respective cores, constitute a differential regulator for controlling the length of the resistance 104 which is included in the circuit 105, 106. The position of the lever is differentially responsive to the line voltage impressed on the coil 85, and to the amount of current passing through coil 115 over circuit 116a—116d. The latter circuit is made

a substantially constant-current circuit by virtue of the regulating function of constant-current regulator 120. Any tendency of the current flow through this circuit 116a—116d to rise above a predetermined value operates through the coil 185 and core 184 to actuate lever 182 for increasing the effective inductance of the variable inductance 168 to change the grid phase relation for decreasing the current flow through the tubes. Conversely, any tendency for the current flow through this circuit to fall below a predetermined value causes the lever 182 to operate in the reverse direction for decreasing the reactance of the variable inductance 168 to increase the current flow through the tubes. Thus, a substantially constant current is maintained through the resistor 108, for affording a substantially constant voltage drop across the resistor, which voltage drop supplies the circuit 105, 106 connecting with the saturable core reactor 45. By making the regulator 100 responsive to the potential in the supply lines 11 and 12, any rated amount of constant current can be established by adjustment of regulator 120, which will change the normal position of lever 101. Assuming now that this lever has a certain normal position corresponding to a certain potential which it is desired to maintain on the supply circuit, an increase of potential in the supply circuit will operate through the potential coil 85 and core 84 to swing the lever 101 in a counterclockwise direction for interposing additional resistance in the circuit of the primary winding 47 of the saturable core reactor 45. The consequent reduction of current flow through said primary winding increases the impedance in the reactance winding 46 so as to reduce the voltage in the supply circuit. Conversely, a decrease in voltage across the supply circuit permits the lever 101 to move in a clockwise direction for reducing the resistance in circuit with the primary winding 47, thereby increasing the current flow through this winding and decreasing the impedance of the reactance winding 46 for raising the voltage in the supply circuit.

Referring now to the modified arrangement illustrated in Figure 5, in this embodiment the two grid controlled arc rectifying tubes 51 and 52 are connected inversely in the supply circuit 11, 12 to control the voltage and current flow to the monocyclic network. The supply line 11, 12 is connected to the primary winding 54 of the anode or power transformer 53. The supply circuit is continued from the secondary winding of this transformer through conductors 11' and 12' to the input diagonal of the monocyclic square 16. The two rectifying tubes 51 and 52 are interposed in reversed parallel relation in one of the conductors 11' or 12'. This reversed relation of the two tubes, wherein one part of the conductor 12' connects to the filament of one tube and the anode of the other, and the continuation of the conductor connects to the anode of the first tube and the filament of the second, enables the two tubes to pass alternating current to the monocyclic network. The phase of the potential applied to the grids is controlled by a phase shifting network which is practically a duplication of that shown in Figure 1, with the exception that the grid transformer 64 is provided with two secondary windings 66, 66', one for each grid. The secondary winding 66 is connected through conductors 71 and 73 with the grid and filament respectively of the tube 51. The other secondary winding 66' is connected through conductors 72 and 73' with the grid and filament respectively of the other tube 52. The two branch paths 71 and 78 of the phase shifting network have the resistor 67 interposed in one of these branch paths, and have the reactances 68, 68' interposed in the other, substantially as previously described. The variable inductance 68 is governed by the motion of the lever 82 in response to the potential impressed on coil 85, which coil is connected across the supply line conductors 11' and 12'. The section 68' of fixed reactance is connected through conductors 91, 92 and 93 with the contacts 132, 132' of the relays 131 and 131'. The windings of the latter relays are connected in series in the load circuits 14 and 14', this arrangement being similar to that illustrated in Figure 1.

In the operation of this embodiment, all current over the supply line to the monocyclic network passes through the tubes 51 and 52, and hence this current is directly subject to the conduction periods of these tubes. In the event of an objectionable rise of potential in the supply line, the potential coil 85 responds thereto and increases the inductance in the phase shifting network, thereby causing the grid voltage to become more out of phase with the anode voltage and reducing the flow of current through the tubes. Conversely, a decrease of potential in the supply circuit reduces the inductance in the phase shifting network, causing the grid voltage to become more in phase with the anode voltage and increasing the flow of current through the tubes. With reference to the control which the relays 131 and 131' in the load circuits exercise over the phase shifting network, under normal current conditions in the load circuit, the relay contacts 132, 132' are closed and hence the fixed reactance 68' is shunted so that it has no effect in the network. However, upon an interruption of the current flow in either load circuit, the relay of that circuit opens its respective contacts and thereby includes the reactance 68' in the network in series with the variable inductance 68. This immediately causes the grid voltages to become more out of phase with the anode voltage and hence reduces the flow of current through the tubes, reducing the voltage impressed on the monocyclic squares and avoiding dangerous voltages in the load circuits. Where only a single load circuit is fed from the supply circuit the single relay in this load circuit will perform this same controlling operation. The control effected through the tubes 51 and 52 necessarily controls the voltage impressed on each monocyclic network because the variation in the time of firing of the tubes determines the points in the voltage cycles at which the voltage is conducted through the tubes.

My improved constant-current system has several characteristic features and advantages which are common to all of the embodiments above described. For example, the current in either of the load circuits 14 or 14' is independent of the load in these circuits. Moreover, the current in the load circuits is directly proportional to the voltage of the supply circuit 11, 12 (or 11', 12'), and is in quadrature with this voltage. Numerically, the current in the load circuit is equal to the primary or supply voltage divided by the reactance of one leg of the monocyclic square. The current in the supply circuit is directly proportional to the secondary load, and is in quadrature with the secondary current. Where the system is used for street lighting, such street lighting circuits operate at high power factor, from which it follows that the primary power factor will also be high. The loss in the inductance elements of the

monocyclic square is very low, and the condensers have practically no power loss.

Inasmuch as the secondary current of a monocyclic network rises and falls as the primary voltage rises and falls, my improved system exercises a direct and efficient regulation in controlling the primary voltage impressed on the primary side of the network. My improved regulating system will hold the impressed voltage to .02 per cent plus 10 and .02 per cent minus, with a variation of 25 per cent in the supply voltage.

By the use of my improved system it is possible in station installations to operate a number of load circuits from one control, and it can also be 15 used to control a number of circuits out of a vault.

While I have illustrated and described what I regard to be the preferred embodiments of my invention, nevertheless it will be understood that such are merely exemplary and that numerous 20 modifications and rearrangements may be made therein without departing from the essence of the invention.

I claim:—

1. In combination, an alternating current supply circuit, a substantially constant current load circuit, a monocyclic square connecting said supply circuit with said load circuit, potential regulating means for controlling the potential of said supply circuit comprising a saturable core reactor 30 and an electron tube, the conduction period of said electron tube governing the flux density in said reactor, and means responsive to the potential of said supply circuit and to the current in said load circuit for controlling the conduction 35 period of said tube.

2. In combination, an alternating current supply circuit, a substantially constant current load circuit, means for transmitting energy therebetween, an electron tube connected to control the 40 potential of said supply circuit, and means responsive to the potential of said supply circuit and to the current flow in said load circuit for controlling said electron tube.

3. In combination, an alternating current supply circuit, a substantially constant current load circuit, a monocyclic square connecting said supply circuit with said load circuit, potential regulating means for controlling the potential of said supply circuit comprising an electron tube characterized by a controllable conduction period, the 50 conduction period of said tube governing said voltage regulating means, and means responsive to the potential of said supply circuit and to the current flow in said load circuit for controlling 55 the conduction period of said tube.

4. In a system of the class described, the combination of an alternating current supply circuit, a substantially constant current load circuit, a monocyclic square connecting said supply circuit 60 with said load circuit, potential regulating means for controlling the potential of said supply circuit comprising a saturable core reactor and an electric valve connected therewith, the conduction period of said electric valve governing the flux 65 density of said reactor, and means responsive to the electrical condition in a part of said system for controlling the conduction period of said valve.

5. In a system of the class described, the combination of an alternating current supply circuit, a substantially constant current load circuit, a monocyclic square connecting said supply circuit with said load circuit, potential regulating means for controlling the potential of said supply circuit, 75 said regulating means comprising a saturable core

reactor and two electron tubes of the grid-controlled arc rectifying type connected therewith to govern the flux density in said reactor, a phase shifting network governing the phase relation of the grid potentials applied to said tubes, and means for automatically controlling said phase shifting network to maintain substantially constant potential on said supply circuit.

6. In a system of the class described, the combination of a substantially constant potential alternating current supply circuit, a substantially constant current load circuit, a monocyclic square connecting said supply circuit with said load circuit, potential regulating means for said supply circuit comprising a saturable core reactor including a reactance winding and a direct current winding, a direct current circuit connected with said direct current winding, two electron tubes of the grid-controlled arc rectifying type connected with said direct current circuit governing the current flow therethrough for varying the flux density in said reactor, a phase shifting network for varying the phase relation between the grid and anode potentials of said tubes, said phase shifting network being capable of displacing the grid potential substantially 180 degrees out of phase with respect to the anode potential, and means for automatically controlling said phase shifting network to maintain substantially constant potential on said supply circuit.

7. In combination, an alternating current supply circuit, a substantially constant current load circuit, means for transmitting energy therebetween, potential regulating means for said supply circuit comprising a variable flux induction transformer, said transformer, said transformer including a primary winding connected across said supply circuit, a secondary winding connected in series in said supply circuit, and a control winding controlling the flux passing between said primary and secondary windings, a saturable core reactor governing the current flow through said control winding, electric valve means controlling the saturation of said reactor, and means for controlling said electric valve means to maintain substantially constant potential on said supply circuit.

8. In combination, an alternating current supply circuit, a substantially constant current load circuit, a monocyclic square connecting said supply circuit with said load circuit, potential regulating means for said supply circuit comprising a variable flux induction transformer, said transformer including a core comprising three legs, a primary winding on one of said legs connected across said supply circuit, a secondary winding on another of said legs adapted to be connected in series in said supply circuit, and a control winding on the other of said legs controlling the flux passing through said core between said primary and secondary windings, a switch for connecting said secondary winding in either a bucking or boosting relation in said supply circuit, a saturable core reactor comprising a reactance winding and a direct current winding, said reactance winding being connected with said control winding, two electron tubes of the grid-controlled arc rectifying type for controlling a direct current flow through said direct current winding, a phase shifting network for varying the phase relation between the grid and anode potentials of said tubes, and means for automatically controlling said phase shifting network to maintain substantially constant potential on said supply circuit.
